Radio Corporation of America, a corporation
of Delaware

Original application September 19, 1931, Serial
No. 563,725. Divided and this application
May 14, 1935, Serial No. 21,343

12 Claims. (Cl. 179—171)

This invention relates to signal transmission systems and more particularly to systems directed to the production and transmission of modulated electrical waves. This application is a division of U. S. application #563,725 filed September 19, 1931 Patent #2,033,231 dated March 10, 1936.

Modulated electrical waves are known in the art as waves or oscillations possessing certain characteristics, one or more of whose characteristics are varied by a modulating device in accordance with the message waves to be transmitted. This modulation may refer to a variation in phase, frequency or amplitude of a high frequency carrier wave where the variation occurs in accordance with signal impulses such as may be caused by sound or electrical waves of a relatively low frequency.

Heretofore, phase modulation has been accomplished by somewhat complicated circuit arrangements which are inserted in the transmitting apparatus. These arrangements, it has been found, are rather expensive and complex, and require careful maintenance.

Accordingly, a primary object of this invention is to secure an improvement in the method of and apparatus for modulating electrical waves. A more specific object is to provide a simple and efficient phase modulation arrangement which may be connected to any existing transmitter with very few changes.

According to one particular embodiment of this invention, these objects are attained by utilizing capacitive and inductive couplings between the modulating device and the output of the carrier current amplifying apparatus. In a specific embodiment, these couplings may take the characteristics of a transmission line over which the wave energy to be phase modulated is propagated. Varying the values of either type of reactance in the line varies the wave propagation and consequently its phase.

Various features of this invention reside in the different circuit arrangements employed for coupling the modulating device to the transmitter apparatus and will appear in the subsequent detailed disclosure.

Referring to the drawings:

Fig. 1 is a schematic diagram of a complete transmitting system employing an artificial line. Phase modulation is attained in this circuit by varying the capacity per unit length of the artificial line;

Figs. 2, 3 and 4 are views illustrating various specific circuit schemes for connecting the arti-

ficial line of Fig. 1 to the other portions of the system.

Fig. 1 illustrates a transmitting system adapted for phase modulation wherein the distributed constants of an artificial line are varied in accordance with the signal wave. A source of wave energy 1 of any nature such as, for example, a crystal or long line control generator, is coupled by way of a transmission circuit included in the rectangle A to a load circuit of any nature shown for purposes of example as an antenna. A limiter device and an amplifier and a frequency multiplier may, if desired, be interposed between the line included in A and the output circuit or the utilization point. An artificial line 20 shown in box A, is connected to the source 1 by leads a and b. The output end of the transmission line 20 is coupled by leads d and e to the load circuit directly or by way of said limiter, power amplifier and frequency multiplier. Elements of the line are also connected by inductances 21 to a lead c which in turn is connected to the means for controlling a characteristic of the line. This means will be described in detail hereinafter. In this particular arrangement glow discharge tubes 19 are utilized as a variable condenser and form part of the distributed capacity of the line. These tubes 19 may be neon tubes, cathode ray tubes or any suitable type of tube wherein an electron stream may be varied to vary the capacity between the electrodes of the tubes and the metallic plate intermediate said electrodes. With no current through the tube the capacity of the tube will only consist of the capacity between the electrodes and the metallic plate. The application of a potential between the electrodes of the tube will cause a current to flow between the electrodes and a glow to strike which will, in turn, act as a conducting material between the electrodes. A variation of the potential across the tube will vary the glow within the tube with a consequent variation in capacity of the tube. Thus, the variation in impedance in the plate circuit of modulator tube 11 will affect the glow tubes and vary their capacity in accordance with the signal wave in an obvious manner. A plurality of radio frequency choke coils 24, 25 of high impedance to the carrier frequency are serially connected in the glow tube circuits. Phase modulation in this arrangement is obtained by continually changing the velocity of the carrier wave transmitted over the artificial line by changing the constants of the line.

The impedance of the plate circuit of tube 11 may be controlled in any manner as, for example, by 55

applying controlling potentials thereto from a source 16 by way of transformer 17 connected with a control electrode of tube 11.

One advantage of this arrangement is that the length of the line may be increased to increase the amount of phase deviation with signal, thus obtaining a decrease in the percentage of variation of the variable distributed constants and consequently obtaining a more linear modulation. Any amplitude modulation caused in this circuit which might be undesirable may be removed in the system by employing limiters or over-loaded amplifiers whose output is limited to a definite value regardless of how much the input is increased. An ordinary vacuum tube amplifier will serve this purpose if it is over-loaded in such manner that its output does not increase in proportion to its input. Such limiting devices are well known in the art and therefore need not be illustrated here. If desired, frequency multipliers may be used to multiply the phase displacement of the modulated wave.

Another advantage of this particular arrangement is that an increase in phase deviation may be obtained by lengthening the artificial line. In such case, frequency multiplication will not be required.

Figs. 2, 3 and 4 illustrate different modulator units which may be employed to replace the apparatus in box A of Fig. 1 in the complete transmitting system.

Referring to Fig. 2, there is shown a glow tube 21 in the form of a variable condenser within which an artificial line is helically wound. If desired this line may be wound around the outside of the tube in very close proximity to the tube. The capacity of the line to ground is varied by changing the glow tube current, thus causing phase modulation of the carrier current impressed on the artificial line.

In Fig. 3 the effective inductance per unit length of the artificial line is modulated by modulating the plate impedance shunted across the inductances 22, 22 which are coupled to the artificial line at various points. In this manner the velocity of the carrier wave propagated along the artificial line is varied in accordance with the variation of the signal wave with a consequent modulation in phase of the carrier.

In Fig. 4 is an arrangement whereby the plate impedance of the modulator tube is serially connected with the capacity of the line to ground. A variation of this plate impedance effectively varies the capacity of the line to ground. The phase modulated wave energy produced in the modulators of the passing signals and appearing at *d* and *e* may be utilized directly or may be passed through an amplitude limiter of the over-loaded tube type before using. If desired, the wave energy may be increased in frequency in 10 and also amplified before utilization.

It should be understood, of course, that this invention is not limited to the specific embodiments disclosed herein, but that various different organizations may be employed which embody the principles of this invention without departing from the spirit and scope thereof.

What I claim is:

1. A phase modulation system comprising a generator of constant frequency wave energy, an output circuit, a transmission line of considerable length as compared to the wave length of said wave energy comprising series inductance and shunt capacity connected between said generator and said output circuit and means connected to

said line for varying the effective electrical length thereof in response to signals to be transmitted.

2. Apparatus as claimed in claim 1, in which said last named means cooperates with the series inductance of said line to vary the effective series inductance of said transmission line at signal frequency.

3. Apparatus as recited in claim 1 in which said last named means cooperates with the shunt capacity of said line to vary the effective shunt capacity of said line at signal frequency.

4. Apparatus as claimed in claim 1, including means for rendering the energy in said output circuit of substantially constant amplitude.

5. A communication system for transmitting message waves, comprising a source of wave energy of carrier wave frequency, an output circuit for said system, an artificial line of considerable length relative to the wave length of said wave energy comprising impedance elements intermediate said source and said output, and means for varying the effective length of said artificial line in accordance with said message wave whereby the phase of the current passing through said lines is varied in accordance with the message waves transmitted.

6. A communication system for transmitting message waves, comprising a source of wave energy of carrier wave frequency, an amplifying device, an artificial line of considerable length relative to the wave length of said wave energy consisting of inductive and capacitive elements intermediate said source and said device, and a modulating element for varying the impedance of either the inductive or capacitive elements of said line in accordance with said message wave whereby the phase of the current passing through said line is varied in accordance with the message waves to be transmitted.

7. A system as defined in claim 6 wherein said capacitive elements comprise at least one glow tube.

8. A device for relaying carrier frequency oscillations and for modulating the phase of the oscillations relayed at signal frequency comprising a source of carrier frequency oscillations, an inductance connected to one terminal of said source, a plurality of reactance elements connecting points on said inductance to the other terminal of said source, and means for varying the value of said reactances at signal frequency to thereby vary the phase of the oscillations impressed on said inductance by said source comprising a thermionic tube having its input electrodes energized at signal frequency, and its anode electrode connected to said reactances.

9. In a phase modulation system, a source of wave energy of substantially constant frequency, a source of modulating potentials, a utilization circuit, an artificial line having distributed inductive reactance and distributed capacitive reactance connecting said source of wave energy to said utilization circuit, and an electron discharge amplifier having input electrodes coupled to said source of modulating potentials and having output electrodes connected in effect in shunt to at least one of said distributed reactances to vary the value thereof at the frequency of said modulating potentials, and thereby vary the velocity of the wave energy along said line to said utilization circuit to thereby vary the phase of said energy reaching said utilization circuit at signal frequency.

10. A phase modulation system as recited in 75

claim 9 wherein said distributed capacitive reactance comprises the capacity between the glow discharge between the electrodes of a discharge device and a plate adjacent the path of said discharge, and in which the output electrodes of said electron discharge tube are connected to the electrodes of said discharge device.

11. A phase modulation system as recited in claim 9 in which said artificial line is of considerable length as compared to the length of the

wave energy of said source of wave energy to thereby insure considerable phase deviation of the wave traveling in said line in accordance with the modulating potentials.

12. A phase modulation system as recited in claim 9 wherein an amplitude limiting device is interposed between said artificial line and said utilization circuit.
